UNITED STATES PATENT OFFICE.

MARK J. PHILLIPS, OF WEBSTER, SOUTH DAKOTA.

ROAD-GRADER.

1,079,579.

Specification of Letters Patent. Patented Nov. 25, 1913.

Application filed April 12, 1913. Serial No. 760,701.

To all whom it may concern:

Be it known that I, MARK J. PHILLIPS, a citizen of the United States, residing at Webster, in the county of Day and State of South Dakota, have invented certain new and useful Improvements in Road-Graders, of which the following is a specification, reference being had to the accompanying drawings.

10 This invention relates to new and useful improvements in road working machines and more particularly to that type of machines which are dragged over the surface of the road and which acts to level and 15 grade the same, the object of the invention being to provide a grader and drag of this character which may be used either as a drag for leveling roads and cutting down hill tops or ruts or grading the surface of 20 the road.

Another object of the invention is to provide a device of this character which will possess advantages in points of efficiency and durability, is inexpensive of manufacture and at the same time is simple in construction and operation.

With the above and other objects in view, my invention consists in the novel features of construction and the combination and 30 arrangement of parts to be hereinafter more fully described, pointed out in the claim and shown in the accompanying drawings, in which—

Figure 1 is a top plan view of a road grader constructed in accordance with my invention; Fig. 2 is a detail transverse sectional view; Fig. 3 is a rear elevation; Fig. 4 is a longitudinal sectional view; Fig. 5 is a detail side elevation illustrating one of the 40 supporting rollers in inoperative position; Fig. 6 is a detail fragmentary bottom plan view of the rear end of the grader; and Fig. 7 is a detail sectional view of the forward end of one of the side beams.

45 Referring more particularly to the drawings, 1 and 2 indicate the convergent side beams, the inner ends of which fit closely together and are rigidly secured, as shown at 3. Secured to the lower longitudinal edges of the beams and arranged upon the inner side thereof are the metallic strips 4, which are adapted to protect the lower edges of the beams 1 and 2 from becoming worn by the continuous scraping of the earth 50 against the side beams. The side beams 1 and 2 are connected adjacent their outer

ends by means of the cross beam 5 and are further connected adjacent their inner ends by means of the cross beam 6. The beams 5 and 6 are suitably connected at their intermediate portions by means of the platform 7. The meeting ends of the side beams 1 and 2 are provided with the concave portions 8 and into which is arranged a curved plate 9, which is adapted to protect the inner 65 ends of the side beams against wear.

It will be apparent that by having the inner ends of the side beams concave in form, as shown at 8, it will provide an exit for the dirt which accumulates between the two side beams. Secured to the inner ends of the side beams and projecting outwardly therefrom is a plate 10 which is adapted to securely pack down earth as it passes through from beneath the ends of the side 75 beams so as not to leave a sharpened ridge in the middle of the road. Suitable brace members 11 are provided, the outer ends of which are secured by means of the bolt 12 to the plate 10 and the other ends of said 80 brace members being suitably secured to the outer side edges of the beams 1 and 2.

Secured to the inner side of the cross beam 5 and arranged upon opposite sides of the platform 7 are the bearing members 13. Arranged within the bearing members 13 is a bolt 14. Mounted upon the bolt 14 and 85 arranged upon each side of the bearing 13 are the supporting brackets 15, between the lower ends of which is supported a wheel 16. Formed integral with the upper end of one of the brackets and projecting at right angles thereto is a lever 17, the outer 90 end of which is normally engaged beneath the hook member 18 secured to the outer end of the cross beam 6. Formed integral with the upper end of the other of said brackets is an arm 19, the outer end of which is provided with aligned projections 20 adapted to be bent upon the lever 17 to 95 securely hold the outer end of the arm in place. From this, it will be apparent that by manipulating the lever 17, the wheel 16 may be raised to the position shown in figure or lowered to its operative supporting 100 position.

Hitch rods 21 are provided, one end of which is secured to the intermediate portion of the cross beam 5 and the other ends thereof secured adjacent the outer ends of the beams 1 and 2, said hitch rods being 110 provided with suitable rings 22 whereby

the whiffletrees may be readily secured thereto. Secured to the forward side of the cross beam 5 is a V-shaped plate 23, which is adapted to throw the dirt from the center of the road into the tracks of the wheels 18 when the same becomes too high in the center.

From the above it will be readily apparent that I have provided a simple and durable road drag and grader whereby the scraper beams are normally resting upon the ground, but when it is desired to transport the device from place to place, the same may be raised and supported upon suitable traction wheels. It will also be apparent that my device is especially adapted for scraping and leveling road beds.

From this construction, it will be seen that the dirt is loosened and scraped toward the center of the road leaving the center higher than the sides so that the water will not settle in the middle of the road. It will also be apparent that my device is extremely simple in construction and can be manufactured at a comparatively low cost.

While I have shown and described the preferred form of my invention, it will be obvious that various changes in the details of construction and in the proportions may be resorted to for successfully carrying my invention into practice without sacrificing any of the novel features or departing from the scope of the appended claim.

What I claim is:—

A road grader including converging side beams having the inner ends rigidly secured and having concaved portions to provide an exit for the dirt which accumulates between the side beams, a curved protecting plate arranged within said concaved portions, and a packing plate secured to the meeting ends of the beams and projecting rearwardly therefrom.

In testimony whereof I hereunto affix my signature in the presence of two witnesses. 45

MARK J. PHILLIPS.
